CIGARETTE AND CIGAR HOLDER

Harry E. Waldrip and Robert J. McMillan,
St. Louis, Mo.

Application August 3, 1940, Serial No. 350,474

2 Claims. (Cl. 131—187)

This invention relates generally to cigarette and cigar holders, and more specifically to cigarette and cigar holders made of paper and like inexpensive material, the predominant object of the invention being to provide an improved cigarette or cigar holder which is very inexpensive and is capable of performing its intended function in a highly efficient manner.

Fig. 1 is a view of a blank from which a cigarette holder is made in accordance with the present invention, a corner portion of the blank being folded over to show the reverse side thereof.

Fig. 2 is an elevation of one of the improved cigarette holders before completion thereof.

Fig. 3 is an enlarged end elevation of the partially completed cigarette holder illustrated in Fig. 2 facing the larger end thereof.

Fig. 4 is a view partly in elevation and partly in vertical section illustrating the manner in which the cigarette holders are supported during a certain phase of the manufacture thereof.

Fig. 5 is an enlarged fragmentary longitudinal section of one of the cigarette holders as it appears prior to its final completion.

Fig. 6 is a view partly in elevation and partly in vertical section illustrating a step in the operation of producing the improved cigarette holders.

Fig. 7 is a sectional view similar to Fig. 5 but illustrating the cigarette holder after an additional step in the operation of producing the cigarette holder has been performed.

Fig. 8 is an elevation of the completed cigarette holder.

In the drawing, wherein is shown for the purpose of illustration, merely, one embodiment of the invention, A designates in Fig. 8 an improved cigarette holder made in accordance with the present invention. The cigarette holder A, as shown in Fig. 8 is formed from a blank 1 of paper, or other suitable material, which is shaped approximately as shown in Fig. 1, it being preferred that the blank 1 be formed of paper highly glazed on one side and very absorptive on the other. The blank is in the shape of the curved surface of a frustum cone and is so proportioned that when rolled it will form a tapered tube of such diameter as to make a convenient mouthpiece at the smaller end and will receive an end portion of a cigarette at its opposite larger end. The blank 1 on one of its surfaces (which is the inner surface of the blank when rolled to provide a tube) is provided with a coating of adhesive substance 2, however, preferably, the entire sur-

face of the blank is not provided with the adhesive coating as a part 3 of the adhesive-receiving surface is free from adhesive as shown in Fig. 1.

The highly glazed surface of the blank, previously mentioned herein, provides the outer surface of the tapered tube when said blank is rolled to provide a tapered tube 4 as shown in Fig. 2. The blank space 3 of the adhesive-receiving face of the blank 1 provides the inner surface of the tapered tube 4, and all paper to paper contacts of portions of the tube 4 have adhesive substance therebetween so that said paper to paper contacting portions are adhesively secured together. While various adhesives may be employed in producing the tapered tube 4 a treated dextrine gum is preferred. When the blank 1 has been rolled to produce the tapered tube 4 said tube preferably consists of three or more thicknesses of paper, the mouth end, or smaller end of the tube, being left circular in shape or flattened slightly to make a mouth piece.

When the tapered tube 4 has been formed as described and the adhesive substance has dried, the mouth end of the tube is provided with a bead 5 so that said mouth end of the tube may be more conveniently gripped in the user's mouth. The bead 5 is produced by dipping the mouth end of the tube 4 in a thermoplastic resin with the result that a body of the resin will adhere to the mouth end of the tube as shown at 5^a in Fig. 5. It has been found that when the mouth end of the tube 4 is dipped into the thermoplastic resin a film 5^b of the material is formed across the end of the tube which closes said end of the tube, and this film 5^b is broken by creating suction, or otherwise causing movement of air within the tube. The suction so created within the tube 4 breaks the film 5^b and shapes the inner portion of the bead 5 as shown in Fig. 7.

One method of providing the tubes 4 of the cigarette holders with the beads 5 is to employ a base member 6 in the form of a board, or the like, which has formed therethrough a plurality of tapered openings 6'. The openings receive end portions of a plurality of tapered tubular supporting elements 7, said tubular supporting elements preferably being a plurality of the tapered tubes 4 which have been cut off at their smaller ends to slightly reduce the lengths thereof. The larger end portions of the supporting elements are secured in the openings 6' of the base member 6 by friction or otherwise, and the tubes 4 to which beads are to be applied are introduced on the supporting elements 7 with sufficient inward force to cause said tubes to be fric-

tionally gripped by said supporting elements. The base member with the tubes 4 attached thereto is then moved to a position where the smaller, mouth ends of the tubes are introduced into the thermoplastic resin contained in a suitable receptacle (not shown), to the approximate depth indicated by the broken line B in Fig. 4. When the mouth ends of the tubes 4 have remained in the thermoplastic resin a sufficient length of time to permit bodies of the resin to adhere thereto they are removed, and at this time the mouth end of each tube 4 is closed by the film 5^b hereinbefore mentioned. The base member 6 is then placed on a suitable supporting frame (not shown) with the tubes 4 extending downwardly, and a suitable suction creating apparatus C is moved along the top face of the base member. As the suction creating apparatus passes over each opening 6' of the base member, suction is created in the associated tube 4, which suction breaks the film 5^b and shapes the inner portion of the bead 5 as shown in Fig. 7.

After the beads 5 have been applied to the tubes 4 as described the plurality of tubes 4 while still supported by the base member 6 are dipped into a body of waterproofing liquid which may be clear or colored as desired, said tubes 4 being preferably dipped into the waterproofing liquid to the approximate depth indicated by the broken line D in Fig. 4. This provides the mouth end portion of the completed cigarette holder A, inside and outside, with a coating of waterproofing material 8 as shown in Fig. 8 to afford protection against mouth moisture. If more than one coating of waterproofing material is desired the tubes 4 may be dipped in the waterproofing liquid as many times as desired. When the coating or coatings of waterproofing material have been applied to the tubes 4 and said waterproofing material has dried, the completed cigarette holders are removed from the supporting elements 7 and are ready for use.

Various thermoplastic resins may be employed to provide the improved cigarette holders with the beads 5, one suitable material being a mixture of a suitable plasticizer, and ester gum of such composition as to make a non-brittle, non-sticky bead. Also a mixture of ester gum, resins, and any suitable plasticizer may be employed to produce a bead having the desired properties. The waterproofing material employed in making the improved cigarette holders may be any non-

toxic, tasteless material that can be applied in film form, either from organic solution of the same, or in melted form. In this connection the use of the Vinylite type synthetic resins, either type "A" or "V" dissolved in any suitable organic solvent is preferred.

We claim:

1. A holder for smoking articles comprising a tapered tube rolled from a sheet of material, the entire wall of said tapered tube being made up of a plurality of thicknesses of said sheet of material, adhesive material applied to such portion of a surface of said sheet of material as to dispose said adhesive material only between all portions of the respective thicknesses of the sheet material in said wall and so that the entire inner surface of the holder is free from adhesive material, a bead formed of thermoplastic material applied to the smaller end of said tapered tube to provide a mouthpiece, said bead being in embracing relation with respect to the end portion of the wall of said tapered tube at said smaller end thereof, and a coating of waterproofing material arranged on the outer and inner surfaces of the smaller portion of said tapered tube and on said bead.
2. A holder for smoking articles comprising a tapered tube rolled from a sheet of material which is provided with a surface portion that is highly absorptive and which provides the inner face of the tapered tube and an opposite surface portion that is glazed and which provides the outer face of the tapered tube, the entire wall of said tapered tube being made up of a plurality of thicknesses of said sheet of material, adhesive material applied to such portion of a surface of said sheet of material as to dispose said adhesive material only between all portions of the respective thicknesses of the sheet material in said wall and so that the entire inner surface of the holder is free from adhesive material, a bead formed of thermoplastic material applied to the smaller end of said tapered tube to provide a mouthpiece, said bead being in embracing relation with respect to the end portion of the wall of said tapered tube at said smaller end thereof, and a coating of waterproofing material arranged on the outer and inner surfaces of the smaller portion of said tapered tube and on said bead.
